UNITED STATES PATENT OFFICE.

JOSEPH HOPKINSON, OF DAYTON, OHIO, ASSIGNOR TO THE COMPUTING SCALE COMPANY, OF DAYTON, OHIO, A CORPORATION OF OHIO.

DESIGN FOR A SCALE-CASING.

50,417.

Specification for Design.

Patented Mar. 6, 1917.

Application filed October 30, 1916. Serial No. 128,624. Term of patent 14 years.

To all whom it may concern:

Be it known that I, JOSEPH HOPKINSON, a citizen of the United States, residing at Dayton, in the county of Montgomery and State of Ohio, have invented a new, original, and ornamental Design for a Scale-Casing, of which the following is a specification, reference being had to the accompanying drawing, forming a part thereof.

In the drawing:

The figure represents a perspective view of a scale casing, showing my new design.

I claim:

An ornamental design for a scale casing, substantially as shown.

JOSEPH HOPKINSON.
